THOMAS M. WILDER, OF HIGHLAND PARK, ILLINOIS.

AUTOMOBILE-RADIATOR AND METHOD OF CONSTRUCTION.

1,302,111.

Specification of Letters Patent. Patented Apr. 29, 1919.

Application filed May 31, 1917. Serial No. 171,364.

To all whom it may concern:

Be it known that I, THOMAS M. WILDER, a citizen of the United States, and a resident of the city of Highland Park, in the county 5 of Lake and State of Illinois, have invented certain new and useful Improvements in Automobile-Radiators and Methods of Construction; and I do hereby declare that the following is a full, clear, and exact description 10 of the same, reference being had to the accompanying drawings; and to the numerals of reference marked thereon, which form a part of this specification.

This invention relates to an improved 15 structure of radiator particularly adapted for use on motor cars, although of course, well adapted for any use whatsoever, wherein it is desirable to cool a fluid by subjection to the heat radiating action of the 20 cells of the radiator. The most generally used and probably most efficient type of radiator now in use is the so-called tubular type of radiator. An objection to this general type of radiator is that there is no 25 lateral connection between the various tubes or cells in the radiator, and the water entering a tube at the upper portion of the radiator is entirely separated from the other water in the radiator while it trickles downwardly through the tube until it reaches a 30 common compartment at the lower end of the radiator.

By my invention, however, the water is 35 permitted to circulate through the radiator both laterally as well as vertically, so that an even distribution of water throughout the cells of the radiator is assured, thereby increasing the cooling effect upon the whole body of water or other fluid passed through 40 the radiator. Furthermore, I purpose providing a cellular or honeycomb type of radiator which may be easily manufactured, and one which, in the case of damage, may be easily repaired.

45 It is an object therefore of this invention to construct a radiator consisting of a series of cells with the cells of each series in communication with the cells laterally adjacent thereto.

50 It is also an object of this invention to construct a cellular type of radiator consisting of a plurality of series of cells with the cells of adjacent series communicating with one another whereby a flow of fluid is permitted throughout all of the cells of the radiator both from the upper to the lower

end of the radiator as well as from side to side thereof.

A further object of the invention is to provide a method or process of conveniently 60 constructing a radiator whereby a cooling medium is permitted to circulate both lengthwise and laterally between tubular passageways formed in said radiator.

Another object of the invention is to provide a method of constructing a radiator which consists of first joining together a pair of apertured strips in reverse position to form the walls of two adjoining tubes with the apertures thereof registering, after 70 which assembled pairs of strips are secured together so that a strip of one pair fits against a strip of another pair forming a tubular passageway therebetween.

It is a further object of this invention to 75 construct a cellular type of radiator built up of angled stamped metal sections which, when laid in registering relation with one another, form cell elements for passage of a fluid therethrough, and with the sections 80 apertured and the elements soldered to one another to afford lateral communication as well as vertical communication between the respective cells of the assembled elements.

Other and further important objects of 85 the invention will be evident from the disclosure in the drawings and specification.

The invention (in a preferred form) is 90 illustrated in the drawings and hereinafter more fully described.

On the drawings:

Figure 1 is a front elevation of a radiator constructed according to the principles of my invention.

Fig. 2 is an enlarged fragmentary elevation of the radiator structure.

Fig. 3 is a detail view taken on line 3-3 of Fig. 2.

Fig. 4 is a sectional detail on line 4-4 of Fig. 2.

Fig. 5 is a sectional detail on line 5-5 of Fig. 4.

As shown on the drawings:

My invention is shown herein in connection with the type of radiator such as is 105 commonly used in motor cars, although it is to be understood, of course, that it may be otherwise used. As shown, what I term the radiator proper consists of a reticulated structure formed of flat tubular elements 110 specially constructed and combined as hereinafter noted to facilitate assembling and

repairing, and this reticulated structure is surrounded by a shell 1, which in the usual construction affords a water space around the reticulated structure. The lower ends 5 of the tubes of which the reticulated structure is composed communicate with the chamber or portion of the passageway at the bottom and the upper ends of the tubes communicate with the chamber or portion of the 10 passageway at the top so that the heated water may circulate by gravity from the upper chamber through the tubes of the reticulated structure, so as to dissipate the heat, and from the tubes into the bottom 15 chamber, and the upper chamber as a tubular extension 2, and a cap therefor as shown for filling the radiator with water or other cooling liquid.

The reticulated radiator structure, as previously stated, is composed of a series of flat tubular elements arranged side to side or with their flat faces adjoining, and each of these tubular elements is composed of a pair of strips of metal 3 and 4, both of which 25 in the present embodiment of my invention have similar transverse corrugations stamped therein and are slightly concave on the inner faces as at 5 and 6, respectively, so that when the strips are arranged in reverse relation, that is with the concave face of one facing the concave face of the other, the edges of the two plates fit together so that they may be readily soldered or otherwise connected to provide a tight joint and 35 form a flat zig-zag tube as clearly shown in Figs. 2 and 5.

A plurality of these tubes are arranged side by side but in reverse relation so that the tips of the corrugations or angular 40 portions of the tube engage and fit against the tips of similar corrugations or angular portions of the tube at each side thereof, and it is an important feature of my invention that communication is afforded between 45 the adjoining tubes where the tips of the corrugations or angular walls thereof engage so that circulation is not only afforded from one end to end of these tubes, but at a plurality of points intermediate the ends 50 thereof with the adjoining tubes, so that the water or cooling liquid may circulate laterally through the reticulated radiator structure as well as up and down therethrough.

To afford such communication the walls 55 3 of the tube at the tip of each corrugation are provided with an elongated perforation 8, extending across the width of the flat tube, which registers with a corresponding opening 7, similarly placed in the wall 4, of 60 the adjoining tube, and the contacting walls around the openings are soldered, welded or united in any other suitable manner to provide a secure connection and prevent leakage at this point.

It is to be particularly noted that this 65 connection whereby communication is afforded between the adjoining tubes would be very difficult if not impossible to make satisfactorily after the flat tubes are completed, and the particular construction of 70 the tubes of my device of half sections stamped so as to fit together and form a tube and having the edges thereof fitting together so that they may be soldered or otherwise joined enables intercommunicating tubes to be provided without difficulty. 75

In constructing the radiator proper, a pair of strips 3 and 4, which are to form the walls of two adjoining tubes are provided with the elongated openings 7 and 8, therein, and 80 laid together in reverse position so that the perforated corrugated wall of each strip faces inwardly and abuts against the tips of the corrugations of the other strip, with the perforations thereof registering with one 85 another, and the abutting portions of these two strips are soldered, welded or otherwise joined together around the openings 7 and 8, to effect a tight joint. Obviously such connection can be easily made as the strips are 90 entirely open at each side and permit convenient access to the place where the connection is to be made. All of the strips of which the radiator is to be constructed, with the possible exception of the outer strips, 95 are assembled in pairs in this manner and thereafter the pairs are assembled so that the strip of one pair fits against a strip of another pair forming a flat tubular passageway therebetween and having the flanges 100 at the edges thereof fitting together so that said strips may be readily soldered or otherwise secured together at the edges without the necessity of making any connections at inaccessible places. Succeeding pairs of the 105 previously assembled strips are added on in like manner one after the other until the structure is built up to the size required for the particular radiator, after which the structure is fitted in the frame 1, and the 110 ends of the tubes connected with the chambers of the shell with which they are intended to communicate. The water, or cooling liquid may then circulate through the flat tubes of which the reticulated structure is 115 composed not only lengthwise thereof but laterally between the tubular passageways at a number of points intermediate of the ends thereof so that thorough circulation is assured and cooling of the liquid rapidly 120 effected.

When it becomes necessary to repair the radiator on account of a break or leakage in one of the strips, the pair of oppositely arranged strips forming the adjoining walls of 125 the adjoining tubes, have the edge joints opened up so that the section may be removed and a new section may be readily

inserted in place thereof and the edges soldered to the edges of the adjoining strips without difficulty.

The tubes of which the reticulated structure is composed may be placed upright as shown in Figs. 2 and 5, thus giving the radiator a diamond grid appearance, or the tubes may be arranged diagonally so that the air passages or openings are square or symmetrical with the outline of the radiator.

I am aware that various details of construction may be varied through a wide range without departing from the principles of this invention, and I therefore do not purpose limiting the patent granted otherwise than necessitated by the prior art.

I claim as my invention:

1. In a radiator the combination of a plurality of elongated sections arranged side by side and secured together along their longitudinal edges, each of said sections comprising a pair of strips previously joined together side by side by connected abutting corresponding inwardly extending projections, said strips being longitudinally concaved on the outer faces thereof and the abutting projections being provided with matching perforations so that when the sections are joined together a longitudinal passageway is formed therebetween communicating laterally through the said matching perforations into a corresponding passageway at each side thereof.

2. In a radiator the combination of sections each consisting of a pair of strips arranged side by side, each strip having a concave outer face with attaching flanges along the longitudinal edges thereof and corresponding longitudinally spaced projections extending inwardly from each strip and having the tips thereof abutting against the tips of the corresponding projections of the other strip to form a plurality of air spaces between the strips, the said abutting projections being connected together and provided with matching perforations affording communication between the outer sides of the

abutting strips, the said sections, each consisting of a pair of strips thus assembled, being arranged side by side with the concave face of each strip facing the concave face of a strip of an adjoining section so that the attaching flanges thereof abut and having the flanges secured together so as to form a passageway extending lengthwise between the facing strips of the adjoining sections, which said passageway communicates with the corresponding passageway at each side thereof through the perforations in the tips of the aforesaid projection.

3. The method of constructing a radiator which consists in forming strips of metal with a longitudinal depression in one side and longitudinally spaced projections on the other side, and perforations in the tips of the projections, then combining the strips in pairs with the longitudinal depressions thereof facing outwardly and the tips of the projections of one strip abutting against the tips of the projections of the other strip to form air spaces between the strips, and the said perforations thereof registering with the perforations of the abutting projections to afford communication between the depressions at the outer sides of the strip, then connecting the abutting tips of the projections to hold the two strips together and seal the passageway formed by the matching perforations, then assembling pairs of thus combined strips side by side with the depression of each strip of each pair facing a depression in a strip of the adjoining pair so as to provide a longitudinal passageway therebetween, and then sealingly connecting the longitudinal edges of the facing strips at each side of the depressions therein.

In testimony whereof I have hereunto subscribed my name in the presence of two subscribing witnesses.

THOMAS M. WILDER.
